UNITED STATES PATENT OFFICE.

THOMAS W. WOOD, OF ASBURY PARK, NEW JERSEY, ASSIGNOR OF ONE-HALF TO THOMAS MILTON SHAFTO, OF SAME PLACE.

SPIRIT-LEVEL.

SPECIFICATION forming part of Letters Patent No. 280,706, dated July 3, 1883.

Application filed February 20, 1883. (No model.)

To all whom it may concern:

Be it known that I, THOMAS W. WOOD, a citizen of the United States, residing at Asbury Park, in the county of Monmouth and State of New Jersey, have invented new and useful Improvements in Spirit-Levels of which the following is a specification.

This invention relates to a spirit-level, the stock of which is constructed of sheet metal, so that the cases containing the vials can be readily adjusted therein.

The peculiar construction of the various parts which constitute my spirit-level is pointed out in the following specification and illustrated in the accompanying drawings, in which—

Figure 1 represents a plan or top view. Fig. 2 is a longitudinal vertical section. Fig. 3 is a transverse section in the plane $x x$; Fig. 2. 20 Fig. 4 is a similar section in the plane $y y$, Fig. 2.

Similar letters indicate corresponding parts.

In the drawings, the letter A designates the stock of my spirit-level. This stock is constructed of two metallic side plates, $a a$, two metallic end pieces, $b b$, a metallic top plate, c , and a metallic bottom plate, d . The end pieces, $b b$, and the top and bottom plates, $c d$, are made of sufficient thickness so that 30 holes can be bored through them to receive the rivets $e e$; and if all the plates are got up with sufficient care, and the end pieces and the top and bottom plates are secured in position by the rivets e , a stock is obtained the 35 opposite edges and sides of which are perfectly parallel to each other, while all the corners form right angles, such qualities being essential for the stock of a spirit-level. At the same time, in the interior of the stock, a space 40 is formed amply large enough for the reception of the cases containing the vials. The top plate, c , is made in three section, $c' c' c'$, the end sections, $c' c'$, being provided at their inner ends with offsets $f g$, respectively, while 45 the middle section, c^2 , is provided at both ends with offsets $h i$, respectively, said offsets being all made of the same depth. The offsets i and g are intended to receive the ends of the top plate, k , of the frame B, which supports the case 50 C, containing the vial D, while the offsets $f h$ serve to support a plate, l , to which is secured

the frame E, which supports the case F, containing the vial G. The plate k is secured in the offsets $i g$ by screws $m n$, and when so secured its outer surface is flush with the top 55 plate, c , of the stock A. In the same manner the plate l is secured in the offsets $f h$ by screws $o p$. Openings q in the side plates, $a a$, of the stock expose the vial G, the vial D being visible through an opening, r , in the plate k . 60

From this description it will be seen that in my hollow metallic stock A the vials D G can be secured with the greatest possible accuracy.

For the purpose of adjusting the vial D, I provide the case C with a rib, s , which is fastened at about the middle of its length to the frame B by means of a pivot, t . In the frame B are secured two screws, $u u$, the conical ends of which catch beneath the ribs s of the case C. (See Fig. 4.) By releasing one of these 70 screws and screwing up the other the vial can be adjusted, and when it has reached the required position it can be firmly locked. The vial G is also adjusted by a pointed screw, v , bearing upon a rib, w , on the case F; but in 75 this case one end of the case is supported by a spring, v' .

What I claim as new, and desire to secure by Letters Patent, is—

1. The combination, substantially as herein-before described, of the case C, which contains the vial D, with the hollow metallic stock A, the top plate of which is provided with offsets $i g$, to admit the plate k of the frame supporting the case C. 80

2. The combination, substantially as herein-before described, of the case C, which contains the vial D, and of the case F, which contains the vial G, with the hollow metallic stock A, the top plate of which is provided with offsets $f h i g$, to receive the plates $l k$ of the frames supporting the cases C F. 85

3. The stock A, constructed of metallic side plates, $a a$, end pieces, $b b$, bottom plate, d , and top plate, c , the end pieces and the top and bottom plates being secured to the side plates, $a a$, by transverse rivets $e e$, substantially as shown and described. 90

4. The combination, with the metallic side plates, $a a$, the end pieces, $b b$, the bottom plate, d , and the sectional top plate, c , of two vials, D G, secured to the top plate, c , substantially in 100

the manner and for the purpose shown and described.

5. The combination, substantially as hereinbefore described, of the case C, containing the vial D, the rib formed at the bottom of said case, the pivot for connecting said rib to the frame B, and the two adjusting-screws *u u*, the conical ends of which bear against the under surface of the rib.

10 6. The combination, substantially as hereinbefore described, of the case F, containing the vial G, the rib formed on the under side of said

case, the pivot for connecting said rib to the frame E, the screw *v*, having a conical end which bears against the under surface of the 15 rib, and the spring *v'*.

In testimony whereof I have hereunto set my hand in the presence of two subscribing witnesses.

THOMAS W. WOOD.
